HOLDER FOR A TELEPHONE BOOK

Carl W. Meyer, 922 W. Lombard, Davenport, Iowa

Filed Aug. 10, 1960, Ser. No. 61,690

Term of patent 14 years

(Cl. D74—9)

FIG. 2

FIG. 1 is a front perspective view of a holder for a telephone book showing my new design; and

FIG. 2 is a rear perspective view thereof.

I claim:

The ornamental design for a holder for a telephone book, substantially as shown.
